UNITED STATES PATENT OFFICE

JAMES P. BURKE, OF WAYNE, NEW JERSEY, ASSIGNOR OF ONE-HALF TO MACK MOLD-ING COMPANY, OF WAYNE, NEW JERSEY, A CORPORATION OF NEW JERSEY, AND ONE-HALF TO ARMSTRONG CORK COMPANY, OF LANCASTER, PENNSYLVANIA, A CORPORATION OF PENNSYLVANIA

DESIGN FOR A CONTAINER CAP

Application filed September 12, 1930. Serial No. 36,945. Term of patent 7 years.

To all whom it may concern:

Be it known that I, JAMES P. BURKE, a citizen of the United States, residing in Wayne, in the county of Passaic and State of New Jersey, have invented a certain new, original, and ornamental Design for Container Caps, of which the following is a specification, reference being had to the accompanying drawings, forming a part thereof, and of which—

I claim:

The ornamental design for a container cap as shown.

JAMES P. BURKE.
